UNITED STATES PATENT OFFICE.

HARRY M. THAYER, OF WOODHULL, ILLINOIS.

SHOE-TONGUE RETAINER.

1,163,573.

Specification of Letters Patent.

Patented Dec. 7, 1915.

Application filed November 30, 1914. Serial No. 874,850.

To all whom it may concern:

Be it known that I, HARRY M. THAYER, a citizen of the United States, residing at Woodhull, in the county of Henry and State 5 of Illinois, have invented certain new and useful Improvements in Shoe-Tongue Retainers, of which the following is a specification.

The present invention relates to an im- 10 proved attachment for footwear and has particular reference to a novel shoe-tongue retaining and supporting device.

In all shoes fastened together by means of a lace string it is customary to provide a 15 tongue or strip of leather attached to the vamp of the shoe which extends upwardly behind the lace to provide a protector or shield for the instep and which at the same time increases the neatness of the shoe. 20 However, this shield or tongue usually becomes creased or rumpled, and because of a lack of support does not stay in its proper place thereby presenting an untidy appearance. That is to say, after a short time, the 25 tongue of the shoe works down from its normal position and wrinkles through the crossed portions of the lace thus shortening up and exposing the instep of the wearer. Accordingly, the present invention contem- 30 plates as its primary object the provision of novel and simple means for holding the shoe-tongue in its proper position under all conditions of use, thereby enhancing the neat appearance of the front of the shoe and 35 requiring the tongue to perform its proper functions.

A further object of the invention is to provide a durable and practical device that may be readily and quickly attached to a 40 shoe-tongue without incurring any appreciable expense, and which will be practically inconspicuous on the shoe.

With the above and other objects in view which will more readily appear as the na- 45 ture of the invention is better understood, the same consists in the novel construction, combination and arrangement of parts hereinafter more fully described and claimed.

Though the idea set forth in the present 50 invention is capable of embodiment in various styles and designs, a preferred and practical form thereof is shown in the accom- panying drawings in which—

Figure 1 is a perspective view showing a 55 shoe unlaced to expose the tongue and showing my improved tongue retainer. Fig. 2

is a view similar to Fig. 1 showing the shoe laced up and my improved device engaging with the lace. Fig. 3 is an enlarged vertical sectional view of a portion of a shoe tongue 60 with the retainer applied. Fig. 4 is a detail enlarged perspective view of my invention.

Similar reference characters designate corresponding parts throughout the several figures of the drawings.

In carrying the present invention into effect, it is proposed to make the same applicable to shoe-tongues at the time the same are placed in the shoe or afterward, and also in this connection, it will be obvious that 70 the same may be applied with equal facility to shoes in use without any alterations or defacing of the shoe-tongue.

Though quite susceptible of structural variations and changes in design, the improved 75 retaining and supporting device A in all cases assumes the form of an attachment capable of being secured to the tongue 1 of a shoe 2 having the usual lacing eyelets and studs 3 and a conventional shoe-lace 4, as 80 shown in Figs. 1 and 2 of the drawing.

With special reference to the structural features of the tongue retainer A it will be observed, particularly by reference to Fig. 4, that the same is preferably made from a 85 strip of spring metal of relatively thin cross-section the upper end of the flat body portion 5 of which may be readily bent into the form of a holding or retaining hook 6 having an outwardly flared edge portion or 90 lip 7. The other end of the body 5 is preferably folded upon itself to provide a holding flange 8 after the said body has been placed in the shoe tongue. That is to say, the hook portion 6 is first formed from the 95 body 5 and then the shoe tongue 1 is slit at suitable intervals in the center near the top so as to provide separate holding webs or straps 9 and 10. The said body 5 of the retainer is then fitted to the tongue by being inserted or threaded through the slits between the straps 9 and 10. After the retainer A is thus in place it may be then permanently secured in position by the lower end thereof being folded over to form the 100 holding flange 8 which embraces the strap 10. It, therefore, appears that any sup- 105 porting stress exerted within the hook 6 ef- fectively pulls upwardly upon the tongue and holds it taut.

In locating the retaining hook A on the shoe tongue it is preferable to arrange the

65

110

same so that the last crossing point of the lace before the tie comes within the hook 6, thereby insuring the tongue being supported throughout its length, and maintained 5 in its proper position, and in no way hindering the usual lacing up of the shoe.

From the foregoing it will be apparent that this invention provides a retaining device for shoe tongues which will positively 10 hold the same in their proper position in relation to the parts of the shoe so that it is impossible for the tongue to wrinkle and shorten up to expose the instep or ankle of the wearer as is now the case, and which 15 will not only preserve the neat appearance of the shoe but at the same time prevent the tongue from being a source of discomfort as heretofore.

I claim:

A shoe-lace engaging device adapted to be 20 applied to a shoe tongue comprising a flat body portion, a permanent arched shoe lace receiving hook formed at the upper end of said body portion and co-extensive therewith, an outwardly flared guide lip on said 25 hook, and a folded flange formed at the other end of said body and adapted to clampingly engage a portion of said shoe tongue to hold the entire device thereto.

In testimony whereof I hereunto affix my 30 signature in the presence of two witnesses.

HARRY M. THAYER.
